UNITED STATES PATENT OFFICE.

CHARLES A. ISLEIB, OF MAYWOOD, NEW JERSEY.

RIBBON BLOCK.

Application filed October 10, 1924. Serial No. 742,752.

To all whom it may concern:

Be it known that I, CHARLES A. ISLEIB, a citizen of the United States, residing at Maywood, in the county of Bergen and 5 State of New Jersey, have invented certain new and useful Improvements in Ribbon Blocks, of which the following is a specification.

This invention has for its object to improve the construction of ribbon blocks so as to produce a stronger, more durable, more perfectly finished and otherwise better block than those now in use without unduly increasing the cost thereof. Occasionally ribbon blocks are made of wood or sheet metal, but more usually of pasteboard or other stiff paper material because of its superior cheapness and lightness. But when made of paper material experience has shown that 10 for the sake of uniform facility and accuracy the steps in the manufacture must be the following, to wit; a cylinder of the paper material to form the body must be inserted at each end into the upstanding flange of a cap of said material with cementing substance, as glue, between the flange of each cap and the corresponding end of the cylinder to bind the caps and body together; this involves considerable 15 facility in assembling the parts and results in a more finished article than if the caps were assembled with the body by the latter being made to receive their flanges, but the block then has this series defect that the 20 first layers of ribbon wound on the block, representing more or less length according to the thinness or delicate texture of the ribbon, become creased by the edges of the cap flanges and as a general rule have to be discarded as waste and unsalable, and 25 besides the blocks do not present a finish at the ends and instead of being square-cut or angular all around are rounded and frequently quite irregular. Another fault with 30 the mentioned type of block is that the flanges of the caps, which are pressed up from the disks in forming the caps, have a tendency to spring back to their original position (in the plane of the disk), and so 35 when the flanges are glued onto the cylinder ends they do not always remain glued down all around, but at points stand out more or less.

My ribbon block is constructed of 40 paper material, but so as to avoid these defects and so as in addition to have superior

strength and durability especially in the portion thereof constituting its cylinder or body.

In the accompanying drawing, 60

Fig. 1 is a side elevation of the improved ribbon block;

Fig. 2 is an end view;

Fig. 3 a section on line 3—3, Fig. 1;

Fig. 4 a side elevation with parts broken away; 65

Fig. 5 a side elevation of parts *a a* and *b'*; and

Fig. 6 a side elevation of part *b*.

My block includes, with the two caps *a* of stiff paper material forming the ends of the block, a two-walled body of stiff paper material, such two walls being indicated by the reference character *b b'*. These two walls are concentric, the cylinders to form them differing in diameter only by as much as the thickness of the material of the caps. The caps and cylindrical walls are united by layers of glue *c* or other cement. The caps are preferably so assembled with the 70 walls, which have their ends cut off true to a plane perpendicular to the axis of each cylindrical wall, that the outer wall at least affords at each end edge the circumferential end angle of the block, which is therefore 75 square-cut all around and in any event presents a finished appearance; in other words, each end of the cylinder extends at least as far as the outer surface of the cap. The assembly of the parts may be accomplished in any way so as to bring them into 80 substantially the relation best shown by Fig. 4, having previously to the assembling applied glue or other cement to the parts so that the ends of the two cylindrical walls 85 and the cap flanges will be left adhering or 90 bound together.

This ribbon block is very much strengthened because of the double-wall formation of its cylindrical part or body and because 100 the material of the block is three-ply at its ends and the flanges of the caps are held by the outer cylinder in close contact all around with the inner cylinder and the cement sets with the parts confined in this relation. Its 105 appearance represents a considerable improvement over the ordinary ribbon block because it is plain-cylindrical from end to end and because the ends of the block are square-cut; and in respect to its appearance 110 no especial skill in forming the block is required. Whatever trifling additional ex-

2
pense is entailed by the inclusion of two cylindrical walls instead of one is very materially offset by the saving of several yards of ribbon to each block because the improved 5 block presents no circumferential shoulders to form creases in the first wrappings of ribbon on the block.

While I have herein described the flanges of the caps as cemented to both cylindrical 10 walls I do not wish it to be understood that this is indispensable. While it is best to cement all these parts together, if they are held together in some other way, as by snugly fitting each other, the cementing 15 might be omitted; thus the caps need not necessarily be cemented to the inner cylinder, or, if the outer cylinder quite snugly fits the cap flanges, cement might be omitted between them.

20 Having thus fully described my invention, what I claim and desire to secure by Letters Patent is:

1. A ribbon block comprising two cylindrical walls each formed of stiff paper material and forming the body of the block and arranged one within and concentric with and spaced from the other and two caps each formed of stiff paper material and forming the ends of the block and each having its

flange lying and held between the two corresponding end portions of the cylindrical walls. 30

2. A ribbon block comprising two cylindrical walls each formed of stiff paper material and forming the body of the block and arranged one within and concentric with and spaced from the other and two caps each formed of stiff paper material and forming the ends of the block and each having its flange lying between the two corresponding end portions of the cylindrical walls and cemented to one of them. 35

3. A ribbon block comprising two cylindrical walls each formed of stiff paper material and forming the body of the block and arranged one within and concentric with and spaced from the other and two caps each formed of stiff paper material and forming the ends of the block and each having its flange lying and held between the two corresponding end portions of the cylindrical walls, the ends of the outer cylinder lying in planes perpendicular to its axis and extending at least as far as the outer surfaces of the caps. 40

55 In testimony whereof I affix my signature.

CHARLES A. ISLEIB.
